ABSTRACT OF THE DISCLOSURE

A thermal cryotron is made by sandwiching layers of materials such as a heated resistive tape having on both of its sides a bifilar niobium-zirconium tape and on the outside of each of the niobium-zirconium tapes an insulating material and a conductive metal strip may be placed (on the outside of the layers). A system for utilizing this switch in a flux pump is described.

My invention relates to an electric flux pumping arrangement and particularly to an electric flux pump in which switching is effected by a thermal cryotron.

In my copending application, "Cryogenic Pumped Rectifier Systems," Ser. No. 642,625 filed May 2, 1967, now Pat. No. 3,356,924, and assigned to the assignee hereof there is disclosed an electric cryogenic flux pumping arrangement and electrical control apparatus for use therewith. The system described therein is particularly concerned with the application of superconductive devices maintained at low temperature environments in the neighborhood of 0-15° Kelvin. Specifically, the application discloses an arrangement including a superconducting component and a superconducting source of varying electrical potential. Lossless superconducting paths are provided for alternately coupling the superconducting lossless source of varying electrical potential in an electric circuit relationship with a superconducting component. The arrangement is completed by switching means which are controlled to give certain switching results and which are connected in each of the alternate superconducting paths for alternately switching the superconducting source of varying electric potential in and out of electric circuit relationship with the superconducting component through alternate ones of the superconducting paths in proper phase relationship with the varying electric potential supplied from the lossless superconducting source. The switching means of this device are controlled by special sensing devices which assure that the switching off occurs at a very small current and in proper time relationship.

My invention concerns itself with a new arrangement of such switching means and the control circuit. In the former invention as set forth above, the switching is effected by magnetically controlled cryotrons. However, magnetically controlled cryotrons are expensive, relatively large and the required electronics is not simple. For example, niobium which is commonly used in these cryotrons has a resistivity of about 1×10^{-6} ohms centimeter. Niobium with 25% zirconium, of this example, has a resistivity of about 25×10^{-6} ohms centimeter. The 75% niobium-25% zirconium mixture cannot be controlled magnetically since the required control fields are too high. Niobium-zirconium, which has a transition temperature of 10.5° Kelvin, is particularly attractive for control by heating. Nb (52%) and Ti (48%) has similar properties and is also suitable for use in a heating cryotron. When the flux pump of the application referred to above is provided with a heating cryotron, the cryotron control becomes simpler and higher efficiency can be obtained. The simplicity possible with such device becomes apparent in considering applicant's present invention where switch-

2

ing is accomplished without the necessity of electronic apparatus in the switching control circuit.

It is an object of my invention to provide a flux pump system and a thermal cryotron of special properties.

It is another object of my invention to provide a flux pump circuit for use with a thermal cryotron.

It is another object of my invention to provide a thermal cryotron having a small time constant and having a high resistance at a low temperature and zero resistance at a still lower temperature.

In brief, my thermal cryotron is made of a material which changes from a non-resistive to a resistive state at a low temperature, an example of such a cryotron being niobium-zirconium tapes arranged in bifilar relationship with a heating element of nickel chrome between them. The NiCr heating element has a very thin film of electric insulating material about it. This cryotron may be sandwiched between two copper plates which have approximately the temperature of liquid helium. Between the cryotron and the copper plate is a thin layer of insulation with a thickness determined by the thermal time constant desired. In operation, the bifilar cryotron tapes of niobium-zirconium are heated by the heating element to a point where they become resistive. The tape is made bifilar, that is doubled back upon itself because for efficient operation the total heat output of the heating element must be absorbed and the heat lost must all pass through the layer of insulation which has a critical thickness to allow only a certain amount of heat to pass under given conditions.

Other objects, features, and many of the attendant advantages of this invention will be appreciated more readily as the same becomes better understood by reference to the following detailed description when considered in connection with the accompanying drawings wherein like parts in each of the several figures are identified by the same reference character.

FIG. 1 shows a thermal cryotron.

FIG. 2 shows one embodiment of a control circuit of a flux pump using a thermal cryotron.

FIG. 3 is a series of current versus time characteristic curves of the circuit represented in FIG. 2 and illustrates the mode of operation of this circuit.

FIG. 4 is a hysteresis loop showing the mode of operation of the saturable reactor.

FIG. 5(a) shows the sharp transition point of a typical thermal cryotron with resistance as a function of the temperature while FIG. 5(b) shows the relationship between temperature, heat generated in the resistive phase, and current for a given thermal switching material.

FIG. 6 shows an improved phase shifting circuit to vary the output voltage of the flux pump from positive to negative and vice versa using the same basic circuit as FIG. 2.

FIGS. 7(a), (b), and (c) shows current and voltage versus time relationships at various points in the apparatus represented in FIG. 6 while FIG. 7(d) shows a hysteresis curve according to the mode of operation of the saturable reactor of FIG. 6.

FIGS. 8(a), (b), and (c) show a phase shifting circuit for operating under reduced power and voltage.

FIGS. 9(a), (b), and (c) show a circuit with switch (in reality electronic switches) and hysteresis curves which can operate under reduced power and voltage.

The thermal cryotron assembly 1 shown in FIG. 1 has a central heater element 2 made of a material, for example, nickel chrome, which remains resistive at very low temperatures so that when an electric current flows through this element, heat is generated. The heater material has a high resistance at very low temperatures so that the body of the heater is small and has as small a heat storage capacity as possible to provide high switching

speed. This very thin element 2 is shown divided into two parts, electricity flowing in one direction in one of the parts and in the opposite direction in the other part. Each of the parts is coated with a very thin layer 3 of electrical insulating material. The thermal cryotron tape elements 4 conduct the electrical currents which are to be switched on or off, and are made of a material having a resistive-nonresistive transition temperature at some very low temperature, for example, 10.5° K. These tapes are of a single tape folded upon itself to accomplish full control of the heat generated by the heater.

Other arrangements of cryotron tape and heater are possible, for example, the cryotron tape may be folded several times and the single heater element placed in the middle of the folds.

The cryotron elements 4 must have as fast a thermal time constant as possible to allow fast switching. Thermal time constant may be defined by the expression:

$$T = Vc/s\lambda$$

where V is the volume of the element; c is the specific heat of material per unit volume; s is the surface area; and λ is the thermal conductivity of the insulating material. To effect the desired small time constant the cryotron tape must have a high resistance in its resistive condition so that it may be small in length and must be exceedingly conductive in its conductive state so that it may have a small cross section and a small volume. The transition point of the material should be at a low temperature because c in the formula above is proportional to the third power of the absolute temperature of the transition point. In this embodiment the cryotron tape is made of niobium-zirconium in a 75% to 25% ratio, although any material having the desired characteristics may be used. For example, the cryotron tape may be made of niobium-titanium alloy. The tape or elements described above comprise the operative cryotron element itself. (The parts in the drawing of FIG. 1 are not shown to scale but for purposes of illustration only.)

The dimensions of the elements of the cryotron should be kept as small as possible so that the amount of heat exchange necessary to go from superconductive to resistive and vice versa is as small as possible. Consequently, for given external conditions the smaller the elements the faster the cryotron switching because less heat addition or subtraction is necessary. In order to apply the thermal cryotron in the flux pump arrangement, two elements are added: a cooling material and a pair of thermal insulating plates 5 of critical heat conductivity which are placed between the cryotron tape and the cooling material as shown in FIG. 1. A cooling plate 6 may be inserted between the heat insulation 5 and the cooling material or may be omitted if desired, and the cooling material of liquid helium (not shown) which cools the plate in this embodiment may be applied directly against the thermal insulating material. The thickness of the thermal insulating material is determined by the losses and the rate at which heat is to be conducted from the cryotron tape 4 to the cooling plate 6 or to the liquid helium as the case may be. It is readily seen from the drawing of FIG. 1 that the amount of heat applied to the cryotron tape can be varied by varying the electric current which is passed through the nickel-chrome heater element. The rate of cooling of the cryotron tape 4 is controlled by the thickness of the thermal insulating material 5 between the tape and the copper cooling plate or the liquid helium depending on the construction of the apparatus. In the case under consideration the transition temperature is about 10.5° K. and liquid helium, which has a boiling point of 4.2° K., is the preferred cooling material. As can readily be seen, if other cryotron materials having other characteristic transition temperatures are used other refrigerants or cooling materials may be used.

After the cryotron tape is made resistive by the heater, the heater current is interrupted and the back current

flowing through the cryotron produces sufficient heat to maintain the cryotron tape in its resistive state. The heat losses are minimized to avoid unnecessary evaporation of liquid helium. At the same time the thermal time constant must be kept small and to effect this result the volume of the tape is kept as small as possible.

A simplified rectification circuit is seen in FIG. 2. The power transmission elements and the coil are superconductive at all times while the cryotron is superconductive part of the time and the heater element is not superconductive. An alternating current square wave generator having a low frequency on the order of 10 cycles per second is applied across the transformer which has a split secondary. Tapped from the center of the secondary winding 8 is a coil 10 which is energized when the circuit is in operation. The transformer with its windings 7 and 8 are inside the low temperature area. Electrically connected to each end of the secondary winding 8 is a bifilar cryotron tape 4. Electrically connected to the other end of each cryotron tape is a saturable core winding 9 which in turn is electrically connected to the free end of coil 10. Electrically connected in parallel across each saturable core winding 9 is a series circuit comprising rectifier 11, a variable resistance 12, and heater element 2. The heater 2 is located adjacent the cryotron tape 4 in the manner shown in FIG. 1 while the rectifier 11 and variable resistance 12 are located outside of the cryogenic temperature zone and are at room temperature so that the resistance may be varied to obtain the desired operating conditions for the heater and to prevent heat losses from the rectifier and resistance from evaporating the liquid helium. That portion of the flux pumping system which operates at cryogenic temperatures is shown enclosed by the dash-dot line which represents a suitable cryogenic housing. Each half of winding 8 is connected in an identical circuit to obtain push-pull operation as flux builds up gradually in the cryogenic central coil 10.

The operation of the device of FIG. 2 can be explained by the curves of FIGS. 3(a), (b), and (c). When cryotron tape 4 is superconducting and cryotron tape 4' is resistive, a current I_1 , as shown in FIG. 3(b), flows through tape 4 and saturable core 9 operates at saturation point 14 shown in FIG. 4. The heater 2 begins to operate as soon as the current I_1 starts to become negative and the entire voltage is across the saturable core winding 9. At this time the cryotron 4 is still superconductive. Therefore, current passes through the rectifier 11 and heater 2. At this point the current ΔI flows through the heater 2 causing heat to be given out from the heater to the adjacent cryotron tape 4. The transition temperature is reached after time Δt and cryotron 4 becomes resistive and the transformer voltage is now across cryotron 4 so that a small negative current i flows through 4 because the saturable core 9 has reached negative saturation and the voltage at the core 9 and the current ΔI has become zero. It is at this point that the exact amount of the insulation of the cryotron becomes important because the current i must produce the right amount of heat so that the cryotron tape temperature is kept approximately constant and at a point just above the transition temperature. When the alternating current voltage reverses, the current i will become positive and equal to the small magnetizing current i_m because the rectifier prevents the current from flowing through the heater. Since the current i_m is not sufficient to provide transition temperature, the cryotron tape will cool and become superconductive. Thus, cryotron tape 4 is again superconductive and the cycle is completed. It is noted that the circuit embodied in FIG. 2 works to rectify the square wave input but will not extract power from the field surrounding the flux coil and will not allow regulation of the voltage across the flux coil.

A similar cycle is taking place in the other half of the circuit with current I_2 building up in cryotron 4. The electric currents I_1 and I_2 are actually many times the value of back current i .

The resistance-superconductive transition point is shown at θ in FIG. 5(a). In this figure the plot of resistance and temperature is shown and the transition point θ is indicated on the temperature axis. FIG. 5(b) shows a graph of thermal transfer rate against temperature with the heavy line indicating the thermal transfer rate through the insulation of the cryotron. At current i_2 the transition temperature is reached, at higher current i_3 the transition temperature is exceeded and at lower currents the cryotron transition temperature cannot be reached.

It is readily apparent that the cryotron arrangement of FIG. 2 has certain limitations. For example, this arrangement can only rectify and cannot extract power from the buildup flux field. An arrangement for overcoming some of these limitations is shown in FIG. 6.

The circuit of FIG. 6 permits the direct current output voltage to the coil 10 to be regulated either positively or negatively. By regulating the variable phase shifter so that the negative part of the voltage curves of FIG. 7 is larger than the positive part, energy is extracted from the field of the coil 10 and returned to the power source.

For a detailed explanation of the influence of phase shifting on direct current output see the article of T. A. Buchhold in "Cryogenics" of August 1964, p. 215, FIG. 6 and the explanatory material. Further description is to be found in application Ser. No. 642,625 referred to above.

The flux pumping arrangement shown in FIG. 6 is in its essentials, similar to that of FIG. 2 with the addition of the electron control circuitry. FIG. 6 has the following changes from FIG. 2. The saturable core winding of FIG. 2 is now replaced by a saturable core transformer winding composed of a primary saturable core winding 15 having two secondary windings 16, 17 arranged as shown in FIG. 6. The upper of the two saturable core secondary windings 16 matches its voltage to the heater and the lower is a retarding coil or winding.

The operation of the variable phase shifter in the apparatus of FIG. 6 is essentially the same as that shown in FIG. 18 of application Ser. No. 642,625 referred to above and this mode of operation is discussed in the article, "Superconductive Power Supply" for the flux pump starting on p. 213 of the Cryogenics Magazine of August 1964. Specifically, the resultant currents passing through the halves of the secondary winding 8 of the transformer of FIG. 6 are shown in (b) and (c) of FIG. 7.

All elements within the dotted line are in a cryogenic temperature environment.

FIG. 7(a) shows the voltage and current effects of applying a phase shift. The operation of FIG. 6 shown in FIG. 7 as follows: The current I_2 flows from time t_2 to time t_5 , shown in FIG. 7(c), and the voltage V_2 through this time is positive and then negative as shown in FIG. 7(a). Current i indicates the current through the resistive cryotron 4 and this is first negative and then positive when the voltage reverses. The positive voltage tends to reduce the cryotron current i to the smaller positive magnetizing current i_m , which would make cryotron 4 superconductive. This is avoided by a retarding current i_R in the coil 17, i.e., the lower half of the saturated secondary coil. This retarding current flows between indicated times t_2 and t_4 . The retarding current i_R is obtained when the amplifier A_1 closes the electronic contact 20 at the time t_2 when the coil 16 produces a voltage to amplifier A_1 . Retarding coil or winding 17 is connected to a positive voltage source 21 through the amplifier switch 20. This switch is closed until time t_4 when the phase shifter produces a pulse 22 shown in FIG. 7(a). Pulse 22 causes the amplifier to open the electronic switch 20 stopping current i_R from flowing through retarding coil 17 and reducing the current to i_m . The cryotron 4 then goes superconductive as soon as enough time has elapsed for it to cool past the transition point.

In the event that the positive magnetizing current going through the saturated windings is too large, it may be

reduced by a small current coming from a negative battery 23.

While in FIG. 6 the heater voltage is supplied by the winding 16, it is clearly possible that winding 16 could be connected to an amplifier which in its turn would energize the heater to the desired temperature.

The electrical circuits described in FIGS. 2 and 6 will operate to best advantage only at full power and direct current voltage. However, under operating conditions it may be necessary to use reduced power and reduced direct current voltage. This would cause considerable loss in efficiency in the circuits referred to above.

When the voltage is reduced, the time constants of the saturable reactor give rise to delays in saturation reaction time which cause the direct current voltage to decrease much faster than the applied alternating current voltage. Described below are two electrical circuits for obviating this difficulty at certain levels.

An electrical circuit which is adapted for use with a small alternating current voltage is shown in FIG. 8 and has only one saturable reactor 9. The operation of this circuit is explained as follows, starting with a negative voltage at the right side of the primary of coil 9 the flux ψ will change along C-d as shown in FIG. 8(b) and the coil secondary winding 24 will cause currents to flow in the series circuit of which it is a part. This electric current in passing through heating resistor 2 will cause the cryotron tape 4 to become resistive. The cryotron tape 4 becomes resistive, for example, at point d of FIG. 9b and develops at its terminals a voltage which causes amplifier A_3 to close the switch 25 thereby bypassing the secondary winding 24 of saturable transformer 9. Since the saturable core is short circuited, its flux will not change until the phase shift circuit opens the switch 35 and the flux increases up to positive saturation.

The heater cryotron has the characteristic that with a smaller voltage on it its resistance decreases about linearly and therefore its losses. Considering the case of which a smaller alternating current voltage is applied, then the series resistor 26 is varied to give a total smaller resistance in the control circuit and the cryotron heating resistor 2 heats in about the same time even with less applied voltage. The operation works in a similar manner as the other embodiments in that the cryotron tape 4 goes resistive, the amplifier A_3 closes the switch 25. The switch 25 will stay closed until the phase shifter opens the switch 25 and the flux moves back from d_2 to saturation. Because of the smaller voltage, d_2 is closer to saturation than d in FIG. 8(b). The advantage of this circuit is that the time needed to reach saturation is now about the same as in the previous two circuits since the core voltage is proportionally smaller. The circuit has the advantage that with smaller voltage the cryotron losses decrease about linearly.

Another circuit which will operate under reduced power and reduced direct current voltage is shown in FIG. 9. The circuit shown in FIG. 9 is shown without phase shifting but nonetheless may be adapted for phase shifting if so desired.

This electric circuit is adapted to avoid time loss due to delays in core saturation. The circuit operates efficiently at either of two voltages or operates at a value equal to the sum of the voltages. The value of these voltages depends upon the value of the saturable reactors shown in FIG. 9. The electric circuit shows two saturable reactors 27, 28 in series, the larger 27 of these reactors may be for about 80% of full voltage and the smaller 28 of the two reactors for about 20% of full voltage. If the total rated voltage is applied, both reactors work in series.

If a small voltage such as 20% is to be applied then the larger reactor 27 will have a small positive bias current I_{b0} as shown in FIG. 9(b) which will keep this core in positive saturation even if a negative back current flows. From this it can be seen that the flux of the larger core 27

does not change and only the smaller core is effective. The electrical circuit shown in FIG. 9 shows a gang switch 29 which is closed for low voltage. When this switch 29 is closed, the larger winding 27 is effectively out of the circuit and only the smaller winding 28 operates at 20% of capacity. Further, the resistance 30 in the circuit is lessened by a predetermined amount to allow the cryotron heater 2 to heat the cryotron sufficiently for normal operation. When full or high voltage is used, the double pole single throw switch 29 is opened and both secondary windings are in the circuit giving the effect of a single winding of 100% value. This circuit has also the advantage in having smaller losses at reduced voltage.

In this electrical circuit, the retarding winding which is needed for phase shifting is not shown, but the circuit is adaptable to this modification.

What I claim as new and desire to secure by Letters Patent of the United States is:

1. A flux pumping arrangement including in combination

a superconducting inductance,
a superconducting source of varying electric potential,
alternate lossless superconducting paths for operatively coupling said source of varying potential in superconducting electric circuit relationship with said superconducting inductance,

a thermal cryotron operatively connected in each of said alternate superconducting paths for alternately switching said superconducting source of varying electric potential in and out of superconducting electric circuit relationship with said superconducting inductance through alternate ones of the superconducting paths, and

control means for said cryotron electrically connected to each path comprising a rectifier, a variable resistance, a resistance heater, and a saturable core winding in series with each other whereby said heater resistor is controlled in desired phase relationship with the varying electric potential.

2. A flux pumping arrangement as set forth in claim 1 in which

said thermal cryotron comprises a bifilar tape having a low resistive-nonresistive transition temperature and said resistance heater is located between and in close proximity to parts of said thermal cryotron tape.

3. A flux pumping arrangement as set forth in claim 2 in which

said saturable core winding is electrically connected by one terminal to said cryotron tape and its other terminal is connected to said superconducting inductance whereby current flows in said heater only when the current in said saturable core is in a certain direction.

4. A flux pumping arrangement as set forth in claim 3 in which

said thermal cryotron is immersed in a cryogenic liquid, and
insulating plates of critical thickness are mounted one lying against each outer side of said thermal cryotron tape to allow a certain rate of thermal conduction of heat away from said cryotron tapes through said insulating plates to the cryogenic liquid surrounding said thermal cryotron.

5. A flux pumping arrangement as set forth in claim 3 in which

said rectifier, said variable resistance, and said resistance heater are in electrical series with each other and connected in parallel with said saturable core whereby said saturable core, said rectifier, and said variable resistance form a control circuit for varying the electric current to said resistance heater.

6. A flux pumping apparatus for full or reduced alternating current voltage including in combination

a superconducting inductance,
a superconducting source of varying electric potential,
alternate lossless superconducting paths for operatively coupling said source of varying potential in superconducting electric circuit relationship with said superconducting inductance,

thermal cryotron tape means operatively connected in each of said alternate superconducting paths for alternately switching said superconducting source of varying electric potential in and out of superconducting electric circuit relationship with said superconducting inductance through alternate ones of the superconducting paths, and
control circuit means comprising

a first circuit comprising
two saturable transformers having their primary windings in electrical series in each superconducting path and their secondary windings in electrical series in said control circuit,

a rectifier, a variable resistor having a switch between one end and the variable tape and a cryotron tape heater in electrical series with said secondary windings, and

a second circuit comprising
a coil, a resistance, a voltage source, and a second switch in series,
said first switch and said second switch being mechanically connected so that both switches may be closed simultaneously when reduced voltage is conducted from said superconducting source.

7. An electrical circuit comprising
a superconducting inductance,
a superconducting source of varying electric potential,
alternate lossless superconducting paths for operatively coupling said source of varying potential in superconducting relationship with said superconducting inductance,

a thermal cryotron for controlling current flow through each superconducting path, and

thermal cryotron control means for varying the direction of energy flow in said circuit from said source of varying electric potential to said superconducting inductance or alternatively from said superconducting inductance to said source, said thermal cryotron control means comprising a saturable core transformer having its primary winding in electrical series with said superconducting inductance and said thermal cryotron and having two windings in the secondary thereof, a first winding being connected in electrical series with a resistor for heating said thermal cryotron, a second winding for retarding the current in said first winding so that the current for heating said thermal cryotron is controlled in a desired phase relationship with said varying electric potential.

8. A flux pumping apparatus for a full or reduced alternating current voltage comprising

a superconducting inductance,
a superconducting source of varying electric potential,
alternate lossless superconducting paths for operatively coupling said source of varying potential in superconducting electric circuit relationship with said superconducting inductance,

a thermal cryotron tape means operatively connected in each of said alternate superconducting paths for alternately switching said superconducting source of varying electric potential in and out of superconducting electric circuit relationship with said superconducting inductance through alternate ones of said superconducting paths,

control means for causing said cryotron tape to alternate between its resistive and non-resistive condition under a variety of levels of maximum electric output of said superconducting source,

said control means comprising a saturable transformer means having a primary winding connected in each of said alternate superconducting paths, a secondary winding connected in electrical series with a cryotron tape heater, a variable resistor, and a rectifier and having a switch in parallel with said secondary winding, a phase shifter connected across said source of electric potential, and an amplifier mechanically connected to said switch for opening and closing said switch, said amplifier being electrically connected to said phase shifter whereby a signal from said phase shifter causes said amplifier to open said switch and said amplifier being electrically connected across said cryotron tape whereby a voltage across said cryotron tape causes said amplifier to close said switch and short circuit said secondary winding.
